UNITED STATES PATENT OFFICE.

GEORGE P. FENNER, OF NEW LONDON, CONNECTICUT.

FRONT OR FEED GUIDE FOR PRINTING-PRESSES.

No. 852,883.

Specification of Letters Patent.

Patented April 30, 1907.

Application filed January 10, 1907. Serial No. 351,727.

To all whom it may concern:

Be it known that I, GEORGE P. FENNER, a citizen of the United States, residing at New London, in the county of New London and State of Connecticut, have invented new and useful Improvements in Front or Feed Guides for Printing-Presses, of which the following is a specification.

The object of this invention is to provide a feed guide which can be adjusted according to the thickness of paper or card board to be fed.

This invention resides in a feed guide of spring material so as to be adjustable as set forth in the following specification and claim and illustrated in the annexed drawing, in which:

Figure 1 shows a side elevation of a guide embodying this invention. Fig. 2 is a plan view of Fig. 1. Fig. 3 is a perspective view of a spring piece.

In this drawing the letter *a* indicates a piece or strip of spring steel or metal. This strip as indicated is cut for part of its length to form two branches or be of skeleton or frame shape. This spring metal piece *a* is attached by fastening device or nut *b* to the feed guide spindle.

In feeding the sheet against the guide such sheet is expected to come into contact with the tongue *c* of the feed board. This sheet is made to rest on the tongue of the feed board and the feed guide *f* also rests on said tongue.

The space between the piece *a* and the tongue on the feed board to do accurate work must be increased and decreased a certain extent, depending upon the thickness of paper or card board which is to be fed to the guides. For this purpose is applied the adjusting screw *d* which taps into the spindle of the feed guide. The lower end of the

screw *d* has a groove which engages a slot in the spring metal, shown at *e*.

The spring material is made to project or reach back of the feed guide front *f* so as to press or hold the sheet in proper contact with the tongue *c* or in position for the gripper to take hold. The sheet as it is moved along the feed board comes into contact with or is stopped by the feed guide *f* and as the latter is raised at the proper moment a sufficient degree the sheet can pass thereunder as it is taken by the grippers. The presser piece *a* prevents the edge of the sheet curling up or getting out of reach of the gripper. Such piece *a* projects or extends back of the feed guide front *f*.

What I claim is:

1. A feed guide comprising a spindle with spring metal presser piece and an adjusting screw for the presser piece said screw being tapped into the spindle of the feed guide and engaging an end portion of the presser piece so as to set the same according to the thickness of the sheet to be guided.

2. A feed guide provided with an adjusting screw and with spring presser piece consisting of an elastic strip secured at one end to the guide, and curved back of said guides and having its other end engaged by said adjusting screw.

3. A feed guide provided with a grooved screw and a spring piece secured at one end to said guide and having its other end slotted to engage the groove in the screw.

In testimony whereof I have hereunto set my hand in the presence of two subscribing witnesses.

GEORGE P. FENNER.
